UNITED STATES PATENT OFFICE.

CLARENCE A. BALDWIN AND MARTIN SWENSON, OF BLOOMFIELD, CONNECTICUT.

CALK.

1,269,897.

Specification of Letters Patent. Patented June 18, 1918.

Application filed March 21, 1917. Serial No. 156,401.

To all whom it may concern:

Be it known that we, CLARENCE A. BALDWIN and MARTIN SWENSON, citizens of the United States, residing at Bloomfield, in the county of Hartford and State of Connecticut, have invented certain new and useful Improvements in Calks, of which the following is a specification, reference being had to the accompanying drawings.

10 This invention relates to certain improvements in calks and it is an object of the invention to provide a novel and improved device of this general character which may be detachably engaged with a shoe and which 15 is effectively maintained in applied position upon a shoe.

The invention consists in the details of construction and in the combination and arrangement of the several parts of our improved calk whereby certain important advantages are attained and the device is rendered simpler, less expensive and otherwise more convenient and advantageous for use, all as will be hereinafter more fully set 25 forth.

The novel features of the invention will hereinafter be definitely claimed.

In order that our invention may be the better understood, we will now proceed to 30 describe the same with reference to the accompanying drawings, wherein—

Figure 1 is a view in bottom plan of a horseshoe illustrating calks applied thereto constructed in accordance with an embodiment of our invention;

Fig. 2 is a sectional view taken substantially on the line 2—2 of Fig. 1;

Fig. 3 is a sectional view taken substantially on the line 3—3 of Fig. 1; and

40 Fig. 4 is a fragmentary view partly in elevation and partly in section illustrating a slightly modified form of our invention.

As disclosed in the accompanying drawings, S denotes a shoe having its inner edge 45 1 concave in cross-section in order to reduce to a minimum the possibility of snow adhering to the shoe and balling up. The toe portion of the shoe is provided at one side of the transverse center thereof with the 50 threaded opening 2 adapted to receive the threaded shank 3 depending from the elongated toe calk 4, said shank 3 being positioned at one side of the longitudinal center of the calk.

55 The end portion of the calk remote from the shank 3 is provided at its base portion

with the laterally directed ear 5 provided with an elongated slot 6 extending longitudinally of the calk. The slot 6 is adapted to register with the threaded opening 7 of a 60 diameter less than that of the opening 2 and positioned in the toe portion of the shoe at the opposite side of the transverse center of the shoe. It is also to be noted that the opening 7 is offset relative to the opening 65 3 and is positioned inwardly thereof. The headed bolt 8 is loosely directed through the slot 6 and adapted for threaded engagement with the opening 7.

The head 9 of the bolt 8 is provided with 70 the groove or slot 10 so that said bolt may be readily removed or applied with a screwdriver or similar implement. Through the medium of the slot 6 it will be perceived that the calk can be applied to shoes of varying 75 sizes.

The heel portion of the shoe at each side thereof is provided with a threaded opening 11 in which is adapted to be engaged the threaded shank 12 depending from the heel 80 calk 14. The lower portion of the calk 14 is provided with the lip or tongue 15 adapted to contact with the shoe and extend longitudinally thereof and is provided with an opening 16 adapted to register with the 85 threaded opening 19 produced in the shoe at a predetermined point inwardly of the threaded opening 11. A bolt 18 similar to the bolt 8 is loosely directed through the opening 16 and adapted for threaded engagement 90 with the opening 19.

It is to be noted that the tongue or lip 15 of one of the heel calks extends laterally of a side face thereof while the tongue or lip of the second heel calk extends laterally 95 from an edge thereof so that when the heel calks are in applied position, the sharpened or engaging edges thereof are substantially perpendicularly related.

If preferred, headed screws of a conventional type may be employed in lieu of the bolts 8 and 18 as indicated at 20 in Fig. 4, and in which arrangement the outer or lower end of the coacting opening in the calk is reamed, as indicated at 21, so that the outer 105 face of the screw will be substantially flush with the outer face of the lip or tongue of the calk 14.

From the foregoing description, it is thought to be obvious that a calk constructed in accordance with our invention is of an extremely simple and comparatively inex-

pensive nature and is particularly well adapted for use by reason of the convenience and facility with which it may be assembled; and it will also be obvious that our invention is susceptible of some change and modification without material departure from the principles and spirit thereof, and for this reason we do not wish to be understood as limiting ourselves to the precise arrangement and formation of the several parts herein shown in carrying out our invention in practice, except as hereinafter claimed.

We claim:

In combination with a horseshoe provided with a pair of transversely spaced threaded openings in the toe portion thereof, said openings being in offset relation in a direction longitudinally of the shoe, an elongated calk provided at one side of its longitudinal

center with a depending shank insertible 20 within the forward opening in the toe portion of the shoe, the inner marginal portion of the calk at its end portion remote from the shank being provided with a laterally directed ear, said ear having an elongated 25 slot extending longitudinally of the calk, and a headed member directed through the slot in the ear and in threaded engagement with the second opening in the toe portion of the shoe.

In testimony whereof we hereunto affix our signatures in the presence of two witnesses.

CLARENCE A. BALDWIN.
MARTIN SWENSON.
